GUN-ROD KIT

Julius Bloch, San Francisco, Calif., assignor to
 Brooks Manufacturing Corporation, a corpora-
 tion of California

Application October 5, 1945, Serial No. 620,493

1 Claim. (Cl. 206—16)

1

This invention relates to a rod kit.

An object of the invention is to provide a compact kit in which a rod and accessories for certain sport or cleaning equipment can be carried in a small space, and which can be easily handled and assembled, and in which parts of the container of the kit cooperate both in holding the parts of the equipment in the container and also in the handling of the equipment in use.

Another object of this invention is to provide a gun-rod kit wherein parts of the gun rod function for completing a compact container of a sectional rod, wherein the parts of the rod and accessory devices can be carried in a convenient small space, yet can be readily assembled for use.

Another object of this invention is to provide a gun-rod kit which is highly useful and simple in construction. Convenience of arrangement, lightness and comparative inexpensive of manufacture are further objects which have been borne in mind in the production and development of the invention.

The essential features of the invention involved in the carrying out of the objections indicated are susceptible to modification, but a preferred embodiment of the invention is shown in the accompanying drawings, in which:

Fig. 1 is a partly fragmental side view of my kit.

Fig. 2 is a sectional view of my kit.

Fig. 3 is a detail view of the mounting of the gun rod in the end plug of the kit.

Fig. 4 is an end view of said mounting, and

Fig. 5 is a partly sectional view of the first section of the gun rod and a mounting ball at its end.

My invention is hereby illustrated in connection with gun-rod and cleaning equipment. A tube 1 forms the body of the container of the kit. A partition 2 across the tube separates the space in the tube 1 into two compartments 3 and 4. Inasmuch as the partition 2 is closer to one end of the tube 1 than to the other, the compartment 3 is longer than the compartment 4.

The gun-rod is made of several sections, each substantially the same length or slightly shorter than the compartment 3 so that the sections when severed can be stored in said compartment 3. Section 6 is the handle section of the gun-rod and it has a handle knob 7 thereon whereby the gun-rod can be held and manipulated. This knob 7 has a reduced plug 8 formed thereon adjacent a shoulder 9. The rod section 6 is suitably fixed centrally into said plug 8 and knob 7.

2

The end of the tube 1 at the longer compartment 3 is slit in a substantially T slit 11 to render it stiffly resilient. The plug 8 of the knob 7 tightly fits into said slotted end of the tube 1 when said handle section 6 of the gun rod is inserted into said compartment 3, and thus the knob 7 functions as a plug and closure for the rod-containing compartment 3 of said kit tube 1.

An intermediate section 12 of said gun-rod 10 is formed with a reduced threaded stem 13 at one end to fit into a threaded socket in the end of the handle section 7. In the other end of said intermediate rod section is a threaded socket 16 into which fits a similar threaded stem of 15 the next rod section. The tip rod section 17 is similar to the intermediate rod section 12.

A suitable tip 18 fits threaded into the socket in the end of the last mentioned section 17. This tip is comparatively short and is adapted in any 20 suitable manner to hold a cleaning medium. This tip 18 is kept in the shorter compartment 4. In this shorter compartment 4 are also stored cleaning accessories such as oil and the like indicated at 19. A plug 21 closes the end of the tube 1 25 at the end of the short compartment 4.

The entire kit is compact. The rod sections are held in the long compartment 3 with the rod handle knob 7 plugging the adjacent end of the tube and the long compartment 3. The other 30 accessories are contained in the short compartment 4. When it is desired to use said gun-rod, then the handle knob 7 is pulled out of the tube 1 removing the handle section 6 therewith. Then the threaded end of the section 6 is threaded together with the fitting end of the next section and then the added sections are screwed in place. Finally the tip from the other compartment is 35 screwed on the tip section and the rod is ready for use. After use the sections are separated 40 from one another, and placed in the respective compartments. The compartment 3 is wide enough to accommodate the other rod sections along the handle section 6. Finally the handle section 6 is inserted into the compartment 3 and 45 the plug 8 of the handle knob 7 is pressed into the open end of the compartment 3 to securely plug the same.

The handle section 6 of the gun rod is mounted 50 in the handle knob 7 by extending the handle section 6 through a bushing 22, which bushing has in its inner end a semi-spherical socket 23. A ball 24 threaded on said end of the handle section 6 fits into said spherical socket 23 and also in a recess 26 within the knob 7. The knob 7 has a pocket 27 55 therein into which the bushing 22 fits tightly.

After the ball 24 and the bushing 22 are mounted on the handle ends of section 6 the bushing 22 is driven into the pocket 27 until the ball 24 is engaged with the bottom socket 26 of the recess 27. The tight fitting bushing 22 thereafter holds the gun rod section 6 in position. Thus the knob 7 functions as a rotatable end of the gun rod as well as the closure of the hollow tube 1 of the kit.

I claim:

A gun-rod kit of the character described, comprising a tube having a compartment longitudinally formed therein and open at an end thereof, a sectional gun-rod formed of a handle section and of other rod sections, detachable connections between said sections, a handle knob on said handle section, a plug formed on said handle knob and fitting into said open end of said compartment to plug the same when said handle section is inserted into the compartment, all of said sections fitting into said compartment along said handle section, a partition in said tube forming the bot-

tom of said compartment, said partition being spaced from the other end of said tube and forming a second compartment for cleaning accessories for said gun rod, and a closure on said second end of said tube.
